UNITED STATES PATENT OFFICE.

FRED E. FARNHAM, OF RUMFORD, MAINE.

LIFTING-JACK.

1,036,204.

Specification of Letters Patent. Patented Aug. 20, 1912.

Application filed February 21, 1912. Serial No. 679,025.

To all whom it may concern:

Be it known that I, FRED E. FARNHAM, a citizen of the United States, and a resident of Rumford, in the county of Oxford and State of Maine, have invented certain new and useful Improvements in Lifting-Jacks, of which the following is a specification.

This invention relates to lifting jacks and directly to that class thereof which are cam 10 actuated.

The object of my improvements is to provide a device of the character specified simple in construction, powerful in action and readily adaptable to a variety of service.

15 In the drawings accompanying this specification is illustrated the preferred embodiment of my improvements. Therein—

Figure 1 is a front elevation partly in section on line 1—1 of Fig. 2. Fig. 2 is a side sectional elevation on line 2, 2 of Fig. 1. Fig. 3 is a front view of a detail of Fig. 2. Fig. 4 is a view similar to Fig. 2 and illustrating modifications of my improvements. Fig. 5 is a rear elevation of the lower portion of Fig. 4. Fig. 6 is a plan view, partly in section on line 6, 6 of Fig. 4, and Fig. 7 is a front elevation of details of Fig. 4.

I am familiar with cam jacks in which a single toothed cam is engaged by a gear and 30 I do not broadly claim such known construction. My improvements comprise a compound cam jack in which two oppositely disposed toothed cams are engaged by one common gear whereby the lifting movement 35 is doubled within the one angle of rotation of the driving gear, the action of the cams balanced and the shearing strain on the gear shaft substantially eliminated.

Case 3 is preferably a cylindrical tube 40 and has rotatably mounted midway its length and transversely thereof, actuating gear 4. Slidably mounted in opposite ends of case 3 are plungers 5, 7 having pivotally mounted at their inner ends opposing cams 45 as 8 on pin 9 of plunger 5. Plunger 7 has similar cam 10 on pin 11. Said cams are provided with gear teeth as 12 on their peripheries for coaction with the teeth of gear 4. Said cam pins 9 and 11 and gear 50 shaft 17 lie in one plane so that shearing stress on shaft 17 is substantially eliminated and the general friction of action reduced to a minimum. Each of said cams is provided with a flange or opposite flanges as 13, 14 55 of cam 8 concentric with its cam shaped periphery for engagement with pins as 15,

16 in case 3 for retaining said cams in engagement with gear 4. For rotating gear 4 I may mount said gear on shaft 17 having bearings in case 3. Said shaft 17 may engage said gear by means of squared portion 18 in square hole 19 of said gear. Outboard end 20 of said shaft may also be squared to conveniently engage a wrench or crank, not shown. Said shaft may be retained in endwise position by means of front plate 21 held in place by heads as 22 of screw pins as 15. Outboard said plate 21 ratchet 23 is fixed to shaft 17 for engagement with pawl 24 pivoted at 25 to case 3. Said ratchet 70 and pawl are efficient for preventing the collapse of said jack from its extended position.

In some cases I prefer to mount modified shaft 27 in a ratchet lever 28 as shown in Figs. 4, 6 and 7 whereby when said shaft and lever are withdrawn said jack will pack into less space. In this modification I provide gear 4 with sleeve portion 26 projecting through the front of case 3 and to said projecting portion I fix ratchet 23. Modified shaft 27 turns freely in lever 28 and has ratchet 29 fixed at its outer end. Pawl 30 is pivotally mounted at 31 on lever 28 and is urged to engagement with ratchet 29 by 85 spring 32.

In some cases it is desirable to employ my improved jack in places too small to permit its insertion. In such cases I employ stirrup 33 whose inreaching head 34 has plug 35 for engagement with socket 36 of cap 37 of plunger 5. Said stirrup is provided with foot 38 for direct engagement with the piece to be lifted or moved. Case 3 has lengthwise tongue 39 thereon for guiding stirrup 33 by engagement with lengthwise groove 40 of said stirrup. I also provide said stirrup with antifriction roll 41 for rolling engagement with the rear face of tongue 39.

The operation of my improved jack is as follows: Shaft 17 or 27 being rotated in a clockwise direction Fig. 1, geared cams 8 and 10 are rotated in an anti-clockwise direction on their respective pivots, fixed in plungers 5 and 7 respectively; said plungers are thereby forced outwardly relative to case 3 and if lower plunger 7 is fixed in position by the engagement of its foot 42 with a fixed abutment as a floor case 3 will be moved upwardly a distance corresponding with the throw of one of cams 8, 10 and upper plunger 5 will be moved up-

wardly a distance equal to the sum of the throws of both cams 8, 10. In rotating shaft 17 or 27 ratchet 23 will be engaged by pawl 24 whereby said plungers 5, 7 and 5 cams 8, 10 will be prevented from running down and dropping the load. When it is desired to collapse the jack and lower the load shaft 17 or 27 is rotated in a clockwise direction sufficiently to free pawl 24 from 10 ratchet 23, when said pawl may be swung upwardly on its pivot and the direction of rotation of shaft 17 or 27 reversed thereby lowering the load.

I claim:—

- 15 1. The combination in a cam jack of two opposing rotatably mounted toothed cams actuated by a common gear therebetween, whereby the bearings of said gear are free of the lifted load.
- 20 2. The combination in a cam jack of a case having a gear pivotally mounted on a fixed bearing therein, a plunger slidably mounted in each end of said case, a toothed cam pivotally mounted on a fixed bearing 25 in each of said plungers for opposite engagement with said gear, whereby the bearings of said gear are free of the lifted load.
- 30 3. The combination in a cam jack of a case having a gear pivotally mounted on a fixed bearing therein, a plunger slidably mounted in each end of said case, a toothed cam pivotally mounted on a fixed bearing 35 in each of said plungers for opposite engagement with said gear, whereby the bearings of said gear are free of the lifted load,

said cam pivots and gear pivot lying constantly in one plane.

4. The combination in a jack, of a case, a plunger slidably mounted in each end thereof, means for sliding said plungers relative to said case, a removable stirrup slidably mounted lengthwise said case and means in the outer ends of said plungers respectively for engagement one at a time with said stirrup. 40

5. The combination in a jack, of a case, a plunger slidably mounted in said case, means for sliding said plunger relative to said case, a stirrup, means lengthwise said case for guiding said stirrup, means for connecting 50 said plunger and stirrup and an anti-friction roller on said stirrup for engaging the guiding means on said case.

6. The combination in a cam jack, of a cylindrical tubular case, a pair of oppositely disposed cylindrical plungers slidably mounted therein, said plungers having transverse slots in their inner ends, a toothed cam pivotally mounted in each plunger slot, and a gear pivotally mounted between said 60 cams in said tubular case for simultaneous engagement with said toothed cams.

Signed at Rumford, in the county of Oxford and State of Maine, this 13th day of February, 1912, before two subscribing witnesses. 65

FRED E. FARNHAM.
